UNITED STATES PATENT OFFICE.

RICHARD WATKIN, OF NEW YORK, N. Y.

STATION-INDICATOR.

1,237,844.

Specification of Letters Patent. Patented Aug. 21, 1917.

Application filed November 8, 1916. Serial No. 129,301.

To all whom it may concern:

Be it known that I, RICHARD WATKIN, a citizen of the United States, and a resident of the city of New York, borough of 5 Manhattan, in the county and State of New York, have invented a new and Improved Station-Indicator, of which the following is a full, clear, and exact description.

The object of the invention is to provide 10 a new and improved station indicator more especially designed for use in cars to display to the passengers the next station, and arranged to work properly on both the outgoing and return trips of the car.

15 In order to accomplish the desired result, use is made of an endless carrier, actuating means imparting a step by step traveling movement to the said carrier, signs pivoted on the said carrier and each provided with 20 a lug, and a fixed member adapted to be engaged by the said lug on the forward travel of the carrier to swing the sign from vertical display position into an upward non-display position.

25 A practical embodiment of the invention is represented in the accompanying drawings forming a part of this specification, in which similar characters of reference indicate corresponding parts in all the views.

30 Figure 1 is a side elevation of the station indicator arranged in a car and adapted to be actuated from one of the side doors of the car;

Fig. 2 is an enlarged cross section of the 35 station indicator on the line 2--2 of Fig. 3;

Fig. 3 is a sectional side elevation of the same on the line 3--3 of Fig. 2;

Fig. 4 is an enlarged sectional side elevation of a portion of the carrier and sundry 40 of the signs; and

Fig. 5 is a perspective view of one of the trunnions of a sign.

The station indicator is mounted in a suitably constructed casing 10, preferably arranged overhead in the middle of a car, and within this casing 10 is arranged an endless carrier 11 provided with signs 12 adapted to be successively displayed through an opening 13 formed in the bottom 14 of the casing 10. Each of the signs 12 is provided on each face with the name of a station, and as many signs are provided as there are stations along the route of the car, but it is expressly understood that only one sign at a 55 time is in vertical or display position and

extends across the car so that the name of the next station can be readily read by persons in either end of the car.

The carrier 11 is in the form of endless sprocket chains 15 passing around sprocket 60 wheels 16 and 17 having their shafts 18 and 19 journaled in suitable bearings in the casing 10. One of the shafts is adapted to be turned intermittently, preferably by means connected with one or other of the doors of 65 the car so that when such door is opened an intermittent or step by step traveling motion is given to the endless carrier 11. For the purpose mentioned, one of the shafts is provided at each outer end with a ratchet 70 wheel 20 engaged by either of two pawls 21 or 22 fulcrumed on a lever 23 having a pin 24 engaging a slot 25 in a bar 26 secured to the sliding door 27 of the car. When the car is going in one direction the pawl 21 is 75 in active position while the pawl 22 is thrown out or in inactive position, as indicated in Fig. 1, and consequently when the door 27 is opened a rocking motion is given to the lever 23 to cause the pawl 21 to turn 80 the ratchet wheel 20 and with it the shaft 18 thus imparting a traveling motion to the endless carrier 11. When the door is closed the lever 23 is returned and the pawl 21 glides over the teeth of the ratchet wheel 20. 85 It is understood that when the pawl 21 is in use the endless carrier is caused to travel in the direction of the arrows indicated in Fig. 3. When the car is on the return trip the pawl 21 is then out of engagement with 90 the ratchet wheel 20 and the pawl 22 is engaged with the ratchet wheel so that on the opening and closing of the door 27 the endless carrier is caused to travel in the inverse direction of the arrows indicated in 95 Fig. 3. It is understood that I do not limit myself to the means shown and described for imparting an intermittent traveling motion to the carrier 11, as the same may vary according to the conditions existing on any 100 particular line of transportation on which the car is used.

Each of the signs 12 is provided at its ends with trunnions 30 journaled in brackets 31 attached to the endless sprocket chains 105 15 to allow the sign to swing from non-display into display position. The bottom 14 of the casing 10 is provided on opposite sides of its opening 13 with track rails 32, 33 for the free ends of the signs 12 to travel on 110

while passing toward the opening 13 or away from the same after a sign is returned from display position into non-display position. The opening 13 is so arranged in 5 width relative to the length of the signs 12 that when a sign reaches a middle position then its free end drops off the corresponding rails 32 or 33 to allow the sign to swing by its own weight downward into vertical display position.

10 In order to swing the sign from the display position upwardly and forwardly, that is, in the direction in which the lower run of the endless carrier is traveling, the following arrangement is made: The trunnions 30 are provided with lugs 34 adapted to project into the path of arms 35 depending from a fixed member 36 attached to the casing 10 and extending at the inside thereof approximately at the middle of the casing. By reference to Fig. 4, it will be noticed that when a sign 12 swings into vertical position at the time it is at the middle of the opening 13 then the lugs 34 of this sign are in engagement with the lower ends of the arms 35, and when the next intermittent movement is given to the endless carrier 11 then the lugs 34 cause the sign to swing upward and forward so that the free end of this 25 sign reaches the beginning ends of the track rails 33 to travel along the same with a view to support the sign in non-display position. It is understood that during this forward movement of the carrier 11 the lugs 34 of the display sign eventually pass out from under the arms 35 while the next following sign swings into vertical position, and its lugs 34 engage arms 35. It is understood that when the carrier 11 travels in the 30 reverse direction of the arrows shown in Fig. 2 during the return trip of the car then the signs leave the tracks 33 to swing successively into display position and to be then swung upward and forwardly into non-display position to engage the tracks 32.

35 The station indicator shown and described is very simple and durable in construction and is composed of comparatively few parts not liable to get out of order easily.

40 Having thus described my invention, I claim as new and desire to secure by Letters Patent:

45 1. In a station indicator, an endless carrier, actuating means imparting a step by step traveling movement to the said carrier, signs pivoted on the said carrier and each provided with a lug at its pivoted end, and a fixed member adapted to be engaged by the said lug on the travel of the carrier in either direction to swing the sign from vertical display position into an upward non-display position.

50 2. In a station indicator a casing adapted to be fastened overhead in a car at the middle thereof, the casing having an opening

in its bottom, an endless carrier mounted in the said casing, actuating means imparting a step by step traveling movement to the said endless carrier, and signs pivoted on the said carrier and held in non-display position by the free ends of the signs engaging the bottom of the casing at opposite sides of the said opening, the latter being such that a sign on reaching a position in the middle of the opening swings down into a vertical 75 display position.

3. In a station indicator, a casing adapted to be fastened overhead in a car at the middle thereof, the casing having an opening in its bottom, an endless carrier mounted in the said casing, actuating means imparting a step by step traveling movement to the said endless carrier, signs pivoted on the said carrier and held in non-display position by the free ends of the signs engaging the bottom of the casing at opposite sides of the said opening, the latter being such that a sign on reaching a position in the middle of the opening swings down into a vertical display position, a lug on the pivotal end of 80 each of the signs, and a member fixed in the casing above the said bottom opening, the said lug of a sign on the latter reaching a display position engaging the said fixed member to swing the sign upwardly and forwardly into non-display position on the next 85 travel of the carrier.

4. In a station indicator, a casing adapted to be fastened overhead, in a car at the middle thereof, the casing having an opening in its bottom, an endless carrier mounted in the said casing, actuating means imparting a step by step traveling movement to the said endless carrier, track rails on the bottom of the casing at opposite sides of the said bottom opening, and signs mounted to swing on the said endless carrier and having their free ends adapted to engage and travel along the said rails to hold the signs in non-display position, the said opening 90 being such that a sign on moving into a position at the middle of the opening has its free end clear of the track rails on one side of the opening to allow the sign to swing 95 down into vertical display position.

5. In a station indicator, a casing adapted to be fastened overhead in a car at the middle thereof, the casing having an opening in its bottom, an endless carrier mounted in the said casing, actuating means imparting a step by step traveling movement to the said endless carrier, track rails on the bottom of the casing at opposite sides of the said bottom opening, signs mounted to swing on the said endless carrier and having their free ends adapted to engage and travel along the said rails to hold the signs in non-display position, the said opening being such that a sign on moving into a position at the middle of the opening has its free end clear 100 105 110 115 120 125 130

of the track rails on one side of the opening to allow the sign to swing down into vertical display position, a lug on the pivoted end of each of the signs, and a member fixed in 5 the casing above the said bottom opening, the said lug of a sign on the latter reaching a display position engaging the said fixed

member to swing the sign upwardly and forwardly into non-display position on the next forward travel of the carrier, the free end of such upwardly swinging sign engaging the tracks on the opposite side of the opening. 10

RICHARD WATKIN.
